UNITED STATES PATENT OFFICE

DOUGLAS GRAY HARVEY, OF DIXON, ILLINOIS, ASSIGNOR TO REYNOLDS WIRE CO., OF DIXON, ILLINOIS, A CORPORATION OF ILLINOIS

SCREEN STRUCTURE

Application filed September 16, 1929. Serial No. 392,760.

My invention relates to screen structures of the type adapted to be positioned over window or door openings and on porches and the like to prevent the entry therein of insects.

It is now customary in screening windows and doors to provide a wooden screen frame which is inserted into the window or door frame and to which the screen is attached. It is apparent that to prevent the entrance of insects it is necessary that this screen frame be made to fit the window or door frame accurately. At the same time, in order to exclude as little light or air as possible, it is necessary that the sides of the frame be relatively narrow. Thus, there is the necessity for an accurately shaped but lightly constructed frame the construction of which requires considerable skill. For this reason it is usually necessary to employ a carpenter to properly construct the frames and mount the wire screen therein. Metal frames of suitable size and shape may be used but they are expensive, are heavy and consequently hard to insert in or remove from the frame, and tend to corrode and thus discolor the adjacent frames or walls. It is also difficult to properly stretch the screen across the opening to provide a uniformly taut screen throughout its area. This is one of the greatest difficulties the average individual encounters in applying screens.

In order to overcome these difficulties I have provided a screen structure which may be easily and properly applied by the average individual, without the use of tools other than a hammer, to the frame itself in the case of windows or if desired to frames of the usual type. It will be apparent that when used upon openings, such as doors, it is necessary to employ a screen frame to permit the screen to be opened and closed. The screen structure comprises a screen arranged to be tacked over the opening and strip material adapted to be positioned on the frame at the edge of the opening, having an inwardly projecting bead for tightening the screen.

One of the objects of my invention is the provision of a screen structure which may be manufactured and applied at a relatively small cost.

I have also aimed to provide a screen structure adapted to be applied directly to a window or door frame eliminating the use of the customary screen frame.

Another object of the invention is the provision of a screen structure having means for easily and uniformly tightening the screen. A still further object of the invention is the provision of a screen structure which may be applied by the average individual with the use of a hammer alone.

Other objects and advantages of my improved structure will become apparent from the following disclosure and the accompanying drawings, in which—

Figure 1 is a perspective showing the screen structure applied to a window frame;

Fig. 2 is a section showing the screen held against the lower sill and is a section on the line 2—2 of Fig. 1;

Fig. 3 is a section on the line 3—3 of Fig. 1 and shows the manner in which the strip material rests against the frame and tightens the wire screen;

Fig. 4 is a view of a corner member showing the reinforcing ribs and a portion of the strip material;

Fig. 5 is a section on the line 5—5 of Fig. 4 and shows the manner in which the strip material is scored, and

Fig. 6 is a section on the line 6—6 of Fig. 4.

The screen structure consists generally in a wire screen designated by the numeral 8 arranged to be positioned over an opening such as that formed by the window frame indicated generally by 9 in Fig. 1. The wire screen 8 may be loosely tacked thereon by means of tacks 10 or other suitable means. While the screen may be laid flat upon the sides 11 and 12 and the top 13 of the frame it is necessary to bend the screen a right angle or more at the bottom and tack the lower end thereof to the sill, since the latter projects out beyond the other members of the frame. The manner in which this is performed is clearly shown in Fig. 2. It will be apparent that burlap, cloth, or the like, may be applied to the frame in like manner.

In order to cover the edges of the wire screen which has been applied to the frame

in the manner indicated strip material designated generally by 14 is applied to the inner edge of the frame 9. This material consists of metal strips having a central portion 15 provided with reinforcing ribs 16 extending crosswise thereof, as best shown in Fig. 4. The sides 17 and 18 of the strip material extend downward on either side of the central portion, as shown in Fig. 5, the side 18 having its lower edge beaded, as shown at 19, to provide a rounded portion thereat instead of a sharp edge such as would normally result from cutting the metal. The side 18 may be bent at a greater angle with respect to the central portion, if desired, than the side 17, as shown in the figure, to present a sharper angle with respect to the screen 8, as will presently be described. When the strip material 14 is applied to the frame 8 the side 18 of the former is positioned to extend over the edge of the frame into the opening, as shown in Fig. 3. The lower edge of the side 17 lies in contact with the frame 9 whereby nails 20 driven through openings in the strip material and into the frame 9 cause the edge 19 which lies in contact with the wire screen 8 to be drawn over the edge of the frame and tightened. It will thus be apparent that if the nails passing through the strip material 22, 23 and 24 on the sides 11, 12, and 13 of the frame are drawn down to approximately the same extent the screen will be uniformly tightened if the edge of the screen in contact with the sill 21 is held stationary.

35 In order to cover the lower edge of the screen in contact with the sill 21 and hold it firmly during the tightening operations described, strip material 25 is positioned thereon as shown in Fig. 2 with the edge 19 thereof holding the screen tightly against the sill 21.

A feature of the invention is the provision of scores 26 and 27 at intervals throughout the length of the strip material, the scores being placed opposite each other, 26 in the side 17 and 27 in the side 18. It will be apparent that the individual seeking to apply the screen structure may easily break the strip material to provide a suitable length thereof, such as a side 23. However, the length thereof conforming to a score in the strip material may be shorter than the desired length whereby a small space may be left at the corner of the frame. This distance will be covered by the ends of the corners presently to be described.

Referring now more particularly to Figs. 4 and 6, the corner members will be seen to be constructed in the same general manner as the strip material. The inner side 28, however, corresponding to the side 18 of the strip material, is bent vertically downward and the central portion 29 corresponding to portion 15 of the strip material is made to extend inward to a point even with the edge 19, as best shown in Fig. 4. A side 32 is similar

to and corresponds to side 17. An outwardly projecting lip 30 is provided on the inner edge of the corner and is arranged to bear against the wire screen at the corner of the frame and tighten the screen thereat. Reinforcing ribs 31 corresponding to ribs 16 in size and shape are impressed in the corner members. The ends 33 and 34 of the corner members are of sufficient length to cover any portion of the frame sides left uncovered due to breaking the strip material at a score point. In the drawings, the length of each end is equal to or slightly greater than the distance between the scores on the strip material.

It will be apparent from the foregoing that I have provided an economical but highly improved screen structure which may be easily, quickly, and conveniently applied by the average individual to produce a tight wire screen, pleasing in appearance. It provides a means for applying screens to openings where the cost has hitherto been prohibitive because of the necessity of employing a carpenter or others skilled in the work to produce frames for the screens and mount the wire screen therein.

While I have thus described and illustrated a specific embodiment of my invention I am aware that numerous alterations may be made therein without departing from the invention and I do not wish to be limited except as required by the prior art and the scope of the appended claims.

I claim:

1. In a screen structure adapted for application to a frame structure defining an opening, a screen over said opening, secured to the face of said frame, strip material attached to the face of said frame near the inner edge thereof to cover the edges of said screen, and means acting between said frame and strip material for tightening said screen.

2. In a screen structure adapted for application to a frame structure defining an opening, a screen positioned over said opening, strip material attached to said frame near the inner edge thereof to cover the edges of said screen, said strip material being provided with transverse scores at intervals to permit easy severance of the material, and means acting between said frame and said strip material for tightening said screen.

3. In a screen structure adapted for application to a frame structure defining an opening, a screen positioned over said opening, strip material attached to said frame near the inner edge thereof to cover the edges of said screen, corner members positioned over the ends of said strip material in at least one corner of said frame, and means acting between said frame and said strip material and corner members to tighten said screen.

4. In a screen structure adapted for application to a frame structure defining an open-

ing, a screen across said opening secured to the face of said frame, strip material attached to the face of said frame at the edge of said opening, having an inwardly projecting side arranged to bear against said screen, and means for moving said side inwardly to tighten said screen.

5. In a screen structure adapted for application to a frame structure defining an opening, a screen positioned across said opening, strip material attached to the face of said frame near the inner edge thereof to cover the edges of said screen, said strip material having an inwardly projecting inner side arranged to bear against said screen near the inner edge of said frame and an inwardly projecting outer side arranged to bear against the face of said frame, and combined means for attaching said strip material to said frame and moving said strip material inwardly whereby said screen is caused to be tightened by contact of said inner side.

6. In a screen structure adapted for application to a frame structure defining an opening, a screen positioned over said opening, strip material attached to the face of said frame near the inner edge thereof to cover the edges of said screen, said strip material having an inwardly projecting inner side arranged to bear against said screen near the inner edge of said frame and an inwardly projecting outer side arranged to bear against the face of said frame, corner members provided with inwardly projecting sides and positioned over the ends of said strip material in at least one corner of said frame, and combined means for attaching said strip material and said corner members to said frame and moving them inwardly whereby said screen is caused to be tightened by contact of said inner sides.

7. In a screen structure having a screen positioned over an opening, strip material positioned at the edge of said opening having a continuous solid central portion provided with a plurality of transverse reinforcing ribs and inwardly projecting side portions transversely scored at equal intervals to permit the strip to be broken.

50. 8. A screen structure comprising a screen adapted to be positioned over an opening, strip material arranged to be positioned upon the frame of said opening from top to bottom and from side to side having transverse scores at intervals therein to permit breaking of the strip at predetermined points and having a plurality of transverse reinforcing ribs, the outer side of said strip material projecting inwardly against the face of said frame and the inner side thereof projecting inwardly against said screen in tightening contact, and corner members arranged to be positioned over adjoining ends of said strip material at the corners of said frame, each of said members being provided with an in-

wardly projecting inner side adapted to engage said screen in tightening contact.

9. In a screen structure, a wire screen arranged to be positioned over a window opening or the like and attached to the window frame, metal screen molding comprising strip material arranged to be broken at intervals to provide side pieces for said frame, and corner members adapted to be positioned over adjoining ends of said side pieces, said side pieces and corner members being provided with inwardly projecting sides arranged to engage said wire screen to tighten it when said side pieces and corner members are nailed to said frame.

In witness of the foregoing I affix my signature.

DOUGLAS GRAY HARVEY.
